[57] CLAIM

The ornamental design for an action doll, as shown and described.

DESCRIPTION

FIG. 1 is a front perspective view of an action doll showing my new design;

FIG. 2 is a bottom perspective view thereof;

FIG. 3 is a front elevational view thereof with the cord and fastener member shown in fragment for ease of illustration;

FIG. 4 is a top plan view thereof;

FIG. 5 is a left side elevational view thereof, the side opposite being substantially a mirror image;

FIG. 6 is a rear elevational view thereof; and

FIG. 7 is a bottom plan view thereof.
